The ornamental design for a scoop turner, as shown and described.

DESCRIPTION

FIG. 1 is a front perspective view of a scoop turner showing our new design.

FIG. 2 is a front elevational view thereof.

FIG. 3 is a back elevational view thereof.

FIG. 4 is a right side elevational view thereof.

FIG. 5 is a left side elevational view thereof.

FIG. 6 is a top plan view thereof.

FIG. 7 is a bottom plan view thereof.

FIG. 8 is a front perspective view of a second embodiment thereof.

FIG. 9 is a front elevational view thereof.

FIG. 10 is a back elevational view thereof.

FIG. 11 is a right side elevational view thereof.

FIG. 12 is a left side elevational view thereof.

FIG. 13 is a top plan view thereof; and,

FIG. 14 is a bottom plan view thereof.

In the drawings, the broken lines in FIGS. 1-14 depict portions of the design that form no part of the claim.
